UNITED STATES PATENT OFFICE.

WILLIAM C. BRIGGS, OF WINSTON SALEM, NORTH CAROLINA.

DESIGN FOR A VENDING-MACHINE CASING.

No. 39,548.

Specification for Design.

Patented Sept. 15, 1908

Application filed June 29, 1908. Serial No. 441,037. Term of patent 14 years.

To all whom it may concern:

Be it known that I, WILLIAM C. BRIGGS, a citizen of the United States, residing at Winston Salem, in the county of Forsyth and State of North Carolina, have invented a new, original, and ornamental Design for a Vending-Machine Casing, of which the following is a specification, reference being had to the accompanying drawing, forming a part thereof.

The figure is a perspective view of a vend-

ing machine casing showing my improved design.

What I claim is,—

The ornamental design for a vending machine casing, substantially as shown in the accompanying drawing.

WILLIAM C. BRIGGS.
